CHECK PRINTING MECHANISM FOR CASH
REGISTERSAugust Radermacher and Heinrich Bruckmann,
Essen, Germany, assignors to Fried. Krupp
Aktiengesellschaft, Essen-on-the-Ruhr, Ger-
manyApplication May 6, 1927, Serial No. 189,373,
and in Germany July 6, 1926

20 Claims. (Cl. 235—3)

The invention relates to a printing mechanism for cash registers which is adapted to issue a plurality of checks in one cash operation.

Printing mechanisms are already known which permit a plurality of entirely equal checks to be issued. It may, however, be desirable to issue either one check only or no check at all instead of a plurality thereof. It may further be desirable to characterize in different manner several checks issued in one cash operation and showing the same record. Finally, it may be advantageous, if a plurality of checks are issued in one cash operation, to have them of different length in order to have space on one of them for handwritten records which are not required with the other check. The object of our invention is to fulfil these conditions.

In order that our invention may be more easily understood, a preferred embodiment of the same is illustrated in the drawings which accompany and form part of this specification. In these drawings:

Fig. 1 is an end view of the printing mechanism constructed according to our invention.

Fig. 2 is a lateral view thereof,

Fig. 3 is a section showing the arrangement of the platen,

Fig. 4 shows the arrangement of the check counter,

Fig. 5 shows two checks issued in one cash operation,

Fig. 6 is a single check as issued.

The type wheels forming the main printing drum 1, see Figs. 2 and 3, are set in the well-known manner from the differential mechanism of the machine. The platen 2 and knife 3 are mounted on a vertically guided common carrier 4 which is actuated by means of a two-armed lever 5, 6 from the curved disk 7 serving for one time inking and two times printing and cutting. The curved disk 7 is loosely mounted on the eccentric portion 8 of a shaft 9. This eccentric portion further carries a rubber drum 10, see Fig. 2, adapted to co-operate, when in operative position, with two feed cams 11 and 12 of different length of a feed and date drum 13. The latter comprises date and numeral type wheels 14 and an engraving 15 such as for impressing "buffet," which appears in dotted lines behind cam 11 in Fig. 2, the wheels 14 and engraving 15 likewise

co-operating with the rubber drum 10. A lever consisting of two arms 16 and 17, rigid to shaft 9, Fig. 2, serves to rock the eccentric 8, the arm 17 of this lever being linked to the arm 19 of a rocker 20. This link connection consists of a rod 18 joined at its upper end to arm 20 and engaging a pin 17a of arm 17 by a groove therein at its lower end. The latter is acted upon by a spring 21 and held in position of rest by a pin 22. In this position the eccentric 8 holds the rubber drum 10 and the curved disk 7 in operative position, Fig. 2. The rocker 20 can be rocked upward by the depression of a key W whereby the eccentric 8 is turned clockwise and the rubber drum 10 is brought out of ready position. This motion of the eccentric 8 further causes the curved disk 7 to come into a position in which the lifting motion of platen 2 and knife 3 is less than normal and thus inoperative. Hence, if key W has been depressed, neither a feed motion takes place nor a check is printed and issued nor the types are inked or an impression is made on the rubber cushion.

Besides the date drum 13 serving to feed the check strip, there is provided still another date drum 23, Fig. 2, that only serves to print the check strip. This date drum 23 carries besides the date and numeral wheels 23a an engraving 24, such as for printing the word "kitchen". Both said date drums 13 and 23 have imparted to them one complete revolution from the pinion 26, Fig. 1, by means of pinions 25. Pinion 25 of feed drum 13 is engaged by a pinion 27, of equal size, Fig. 1, which is rigidly connected to the curved disk 7 and remains in mesh with pinion 25 even if disk 7 is rocked.

An eccentrically mounted rubber drum 28, Fig. 2, is adapted to co-operate with the date drum 23. An arm 29 fast on the shaft 30 of said rubber drum 28 is hinged to an arm 32 of a rocker 33 by means of a rod 31. The rocker 33 is held in position of rest by spring 21 and abuts in this position on pin 22. In this position shaft 30 holds the rubber drum 28 out of ready position, see Fig. 2. Arm 32 is further connected by a rod 34 to a pitman 35 which embraces the axle 36 with a slot and is rocked about this axle when arm 32 is rocked. A roller 37 of pitman 35 co-operates with a cam disk 39 under the action of a spring 38. In the position of rest, Fig. 2, the 100

lower end of pitman 35 engages under arm 16 of shaft 9 by means of a pin 40.

By depressing key *Sp* the rocker 33 is lowered and arm 32 is rocked clockwise. When this takes place, rod 31 rocks arm 29 of shaft 30 counter-clockwise whereby rubber drum 28 is brought into ready position. Furthermore, rod 34 rocks pitman 35 clockwise about axle 36 whereby pin 40 is swung out of the range of arm 16 so that in one revolution of the curved disk 7 in the cash operation the arm 16 is not acted upon and rubber drum 10 and curved disk 7 remain in ready position. Hence, when key *Sp* has been depressed, the check strip receives, upon the first feed motion caused by cam 11, from the date drums 13 and 23 on two places first an impression showing date and number, the first of these impressions further containing from the engraving 15 the word "buffet", whilst the second impression still shows the word "kitchen" from engraving 24. The setting of a type wheel mounted on the same axle as the amount type wheels 1 and having the types *W*, *G*, and *Sp* may be effected in a manner well known in the cash register art according to one of the keys *W*, *G*, or *Sp* depressed, as is illustrated by the setting of the sellers type wheel in the patent to Breitling, No. 1,649,443, Nov. 15, 1927. After the first feed motion the first impression of the entered amount takes place and of the character *Sp* by means of platen 2, and the first check showing the impression "Buffet" is cut off, Fig. 5. Due to the greater length of the second check a space for hand-written records is offered thereon.

A third key denoted on its knob by *G* is provided besides keys *W* and *Sp*, but does not co-operate with either of the rockers 20, 33. Therefore, upon depressing key *G* the machine is released with both rubber drums 10, 28 remaining in normal position, more particularly drum 10 and with it curved disk 7 remain in operative position, and drum 28 out of operative position. In the subsequent cash operation therefore only the date drum 13 executes an impression with the first feed motion. Then the impression of the set amount and of the character *G* takes place in a conventional manner by means of platen 2 and the check is cut off, Fig. 6, platen and knife being operated by cam 7 over lever 6 and carrier 4. Before the second feed cam 12 has arrived at the rubber drum 10, pitman 35 is raised by the cam disk 39 acting upon roller 37, arm 16 is engaged by pin 40 and so rocked that rubber drum 10 and curved disk 7 come out of operative range. When this takes place, pin 17a travels in a slot 17b of rod 18 without acting upon this rod. A spring 17c tends to return lever 16 to its normal position as shown in Fig. 2. When key *G* is depressed, feed motion for and impression on a second check thus do not take place and one check only is issued.

The specific manner of unlocking the drive shaft for the operation of a machine cycle by the actuation of any one of the three keys does not constitute a feature of this invention. It may be effected in the manner shown in the patent to Breitling, No. 1,539,461, May 26, 1925.

The two secondary printing members, viz. the date drums 13 and 23, co-operate each with a special ink roller 41 and 42, respectively, which may be differently inked. This permits the issuance of two checks in one cash operation each having a differently colored impression.

To feed the consecutive numbers in the check

counter of the two date drums, an actuator 43, Fig. 4, is provided, the tongues 44 and 45 of which co-operate with the two feed wheels 46 and 47 of the check counters. An arm 48 is rockably mounted below another tongue 52 of actuator 43, and is provided with a pin 51 engaging in a slot 50 in the lower extension of rod 18. Upward motion of rod 18 causes a clockwise rocking of arm 48 which swings tongues 44 and 45 out of the path of the feed wheels 46 and 47. When key *W* is depressed, any counting motion of the two check counters does not take place, whilst with the keys *G* or *Sp* depressed, the feed motion of wheels 46 and 47 takes place in common.

In the embodiment hereinbefore described two secondary printing members are provided for, viz. the two date drums, one of which forms at the same time a feed drum, while both drums carry different engravings. The invention may be employed, however, also in a printing mechanism having no date drum and in which date and number is printed in one line by the types set by the machine. If no date drum is provided for, the two secondary printing members (engravings 15 and 24) are arranged on the drum 13 which in this case serves to feed motion only. If the second date drum is omitted, also its companion drum 28 and thrust rod 31 are unnecessary.

To summarize the operation of the machine: The machine is normally set to issue a single check of the type illustrated in Fig. 6. The release of the machine from its position shown in Fig. 2, by the depression of key *G*, serves to release the driving mechanism thereof to feed the check strip forward by the conjoint action of feed cam 11 and counter drum 10. The suitable engraving upon drum 13 is also impressed at that time. The impression of the amount and the designation *G* by the printing drum and the platen is executed after nearly half a rotation of the curved disc 7, in the course of the machine cycle. In the subsequent half cycle, arm 16 contacts through elements 40, 35, 37 and 39 to rock the counter drum 10 out of position, so that when feed cam 12 reaches its lower position, it has no structure to co-operate therewith to effect a feeding operation. The position of operation of the knife and platen is likewise lowered so as to render these elements inoperative. In the alternate mode of operation by depressing key *W*, counter drum 10 and curved disc 7 which actuates the knife and platen are initially depressed, and registration is effected without the issuing of any check strip, since even feed cam 11 does not engage with the counter drum. Also the counter structures, illustrated in Fig. 4 are not affected during the machine operation by virtue of the rocking of tongues 44 and 45 out of their path. In the further alternate mode of operation for the issuing of two checks illustrated in Fig. 5, by the depression of key *Sp*, counter drum 28 is rocked into an engaging position with the printing drum 23, fixed with suitable engravings. Key *Sp* also serves to rock element 40 out of engagement with arm 16, so that counter drum 10 will not be rocked in the latter portion of the machine cycle, but will remain in position to co-operate with the second feed cam 12. This results in the issue of a long check, adapted to be marked with desired notations in addition to the check normally issued by the machine.

What we claim as our invention and desire to secure by Letters Patent, is:

1. In a machine of the class described, a check strip feed mechanism comprising a feed drum, a plurality of feed cams on said drum, a counter drum adapted to cooperate with said feed cams, and means actuated by the driving mechanism of the machine for withdrawing said counter drum during the passage of one of said feed cams past said counter drum. 80
2. In a machine of the class described, a check strip feed mechanism comprising a feed drum, a plurality of feed cams on said drum, printing types on said drum, a counter drum adapted to cooperate with said feed cams and printing types, a second drum, printing types on said second drum, a second counter drum adapted to cooperate with said second drum said second counter drum being normally in inoperative position, connections between said first mentioned counter drum and the driving mechanism of the machine adapted to rock said first mentioned counter drum out of operative position during the passage of one of said feed cams, and manipulative means for simultaneously disengaging said connections and moving said second counter drum into operative position. 85
3. In a machine of the class described, a platen, a cam disk adapted to impart to said platen a plurality of printing motions during one operation of the machine, a feed drum for a check strip, feed cams on said drum, a counter drum adapted to cooperate with said feed cams, each of said feed cams being adapted to impart a feed motion to a check strip in accord with a determined printing motion of said platen, a common support for said cam disk and said counter drum, and means for rocking said support to simultaneously render inoperative said platen and said feed cams comprising disengageable connections between said support and the driving mechanism of the machine adapted to rock said support at a determined moment in the operation of the machine, and manipulative means for controlling said connections. 90
4. In a machine of the class described, a platen, a cam disk adapted to impart to said platen a plurality of printing motions during one operation of the machine, means rockably supporting said cam disk, a check strip feed drum, feed cams on said drum, a counter drum cooperating with said feed cams, each of said feed cams being adapted to impart a feeding motion to the check strip in accord with a determined printing motion of said platen, means rockably supporting said counter drum, connections between the driving mechanism of the machine and the means supporting said cam disk and said counter drum adapted to rock said supporting means during the passage of one of said feed cams past said counter drum to render said platen and said one feed cam inoperative, and manipulative means for disengaging said connections. 100
5. In a machine of the class described, a platen, a cam disk adapted to impart to said platen a plurality of printing motions during one operation of the machine, means rockably supporting said cam disk, a check strip feed drum, feed cams on said drum, a counter drum cooperating with said feed cams, each of said feed cams being adapted to impart a feeding motion to the check strip in accord with a determined printing motion of said platen, means rockably supporting said counter drum, connections between the driving mechanism of the machine and the means supporting said cam disk and said counter drum adapted to rock said supporting means during the passage of one of said feed cams past said counter drum to render said platen and said one feed cam inoperative, and manipulative means for disengaging said connections. 110
6. In a machine of the class described, a check feeding mechanism and a printing mechanism adapted to execute two feeding and printing motions in one operation of the machine, means actuated by the driving mechanism of the machine during a normal operation for rendering said feeding and printing mechanisms inoperative during one of their feeding and printing periods, and manipulative means for rendering said mechanisms effective during the feeding and printing period in which they are normally inoperative. 115
7. In a machine of the class described, a check strip feed mechanism comprising a feed drum, a plurality of feed cams on said drum, a counter drum adapted to cooperate with said feed cams, means rockably supporting said counter drum, an arm fast on said support, a rod, means disengageably connecting said rod to said arm, a cam driven by the driving mechanism of the machine, a follower on said rod cooperating with said cam, said cam being adapted to rock said support during the passage of one of said feed cams past said counter drum to render said one feed cam inoperative, and manipulative means for disengaging said rod from said arm. 120
8. In a device of the class described, two printing drums adapted to be rotated by the driving mechanism of the machine, two check strip feed cams on one of said drums, a counter drum cooperating with said latter one of the drums normally in operative position, a counter drum cooperating with the other of said printing drums normally in inoperative position, means operated by the driving mechanism of the machine for throwing said first-mentioned counter drum out of operative position during the passage of one feed cam, and manipulative means for rendering both feed cams operative by making said first-mentioned counter drum constantly operative. 125
9. In a device of the class described, two printing drums adapted to be rotated by the driving mechanism of the machine, two check strip feed cams on one of said drums, a counter drum cooperating with said latter one of the drums normally in operative position, a counter drum cooperating with the other of said printing drums normally in inoperative position, means actuated by the driving mechanism of the machine for throwing said first-mentioned counter drum out of operative position during the passage of one feed cam, and manipulative means for simultaneously throwing said second-mentioned counter drum into operative position and rendering the means for throwing said first-mentioned counter drum out of operative position ineffective. 130
10. In a machine of the class described, a check strip feed mechanism comprising a feed drum, a plurality of feed cams on said drum, a counter drum adapted to cooperate with said feed cams, means actuated by the driving mechanism of the machine for withdrawing said counter drum during the passage of one of said feed cams past said counter drum, and control means connected to said counter drum for withdrawing said drum during the passage of a plurality of feed cams past said counter drum. 140
11. In a machine of the class described, a 145
12. In a machine of the class described, a 150
13. In a machine of the class described, a 155

- check strip feed mechanism comprising a feed drum, a plurality of feed cams on said feed drum, a counter drum adapted to cooperate with said feed drum, a support for said counter drum, a 5 disengageable transmission unit extending between the driving mechanism of the machine and said support for withdrawing said counter drum during the passage of one of said feed cams past said counter drum, control means for disengaging said transmission unit for excluding the withdrawal of the counter drum, and a second control means operative upon said support for causing said counter drum to be withdrawn during the 10 passage of a plurality of feed cams past said counter drum.
12. In a machine of the class described, a platen, a cam disk adapted to impart a printing motion to said platen, a feed drum for a check strip, a counter drum cooperating with said feed drum, a common support for said cam disk and said counter drum, a disengageable transmission unit extending between the driving mechanism of the machine and said support for rocking said counter drum and said cam disk during a pre-determined portion of the machine operation, control means for disengaging said transmission unit for excluding the rocking movement of the counter drum and cam disk, and a second control means operative upon said support for rocking said counter drum and said cam disk to simultaneously render inoperative said feed drum and platen.
13. In a machine of the class described, a platen, a cam disk adapted to impart to said platen a plurality of printing motions during one operation of the machine, a feed drum for a check strip, feed cams on said drum, a counter drum adapted to cooperate with said feed cams, each of said feed cams being adapted to impart a 35 feed motion to a check strip in accord with a determined printing motion of said platen, means actuated by the driving mechanism of the machine for withdrawing said counter drum and cam disk during the passage of one of said feed cams past said counter drum to render said platen and feed cams inoperative during one of the printing and feeding periods, and control means connected to said counter drum and cam disk for withdrawing said counter drum and cam disk 40 during the passage of a plurality of feed cams past said counter drum to render said platen and feed cams inoperative during a plurality of printing and feeding periods.
14. In a machine of the class described, a platen, a cam disk adapted to impart to said platen a plurality of printing motions during one operation of the machine, a drum, feed cams on said drum, each of said feed cams being adapted to impart a feeding motion to a check strip in 45 accord with a determined printing motion of said platen, a counter drum adapted to cooperate with said feed cams, a common support for said cam disk and said counter drum, an arm on said support, a rod, means disengageably connecting said rod to said arm, a cam driven by the driving mechanism of the machine, a follower on said rod cooperating with said cam, said cam being adapted to rock said support during the passage of one of said feed cams past said counter drum 50 to render said feed cam inoperative, control means for disengaging said connecting means between said rod and arm to exclude the rocking movement of said support, and a second control means operative upon said support for rocking said counter drum and said cam disk to simultaneously render inoperative said feeding drum and platen.
15. In a machine of the class described, a main printing member having type wheels for printing amounts, a plurality of additional printing members adapted to print upon different sections of a check strip, a feeding device having a plurality of feeding elements corresponding to said additional printing members adapted to feed the sections of the check strip into the field of operation of said main printing member, means for selectively rendering said feeding elements effective, and means for selectively rendering operative said printing members corresponding to the effective operation of said feeding elements.
16. In a machine of the class described, a main printing member having type wheels for printing amounts, a plurality of additional printing members adapted to print upon different sections of a check strip, a feeding device having a plurality of feeding elements corresponding to said additional printing members adapted to feed the sections of the check strip into the field of operation of said main printing member, means for selectively rendering said feeding elements effective, means for selectively rendering operative said printing members corresponding to the effective operation of said feeding elements, and means for causing said main printing member to print upon said sections as they arrive in position.
17. In a machine of the class described, a main printing member having type wheels for printing amounts, a plurality of additional printing members comprising engravings of different indications or surfaces adapted to be inked in different colors, said members being adapted to print upon different sections of a check strip, a feeding device having a plurality of feeding elements corresponding to said additional printing members adapted to feed the sections of the check strip into the field of operation of said main printing member, means for selectively rendering said feeding elements effective, and means for selectively rendering operative said printing members corresponding to the effective operation of said feeding elements.
18. In a machine of the class described, a main printing member having type wheels for printing amounts, a plurality of additional printing members adapted to print upon different sections of a check strip, a feeding device having a plurality of feeding elements corresponding to said additional printing members adapted to feed the sections of the check strip into the field of operation of said main printing member, means for selectively rendering said feeding elements effective, means for selectively rendering operative said printing members corresponding to the effective operation of said feeding elements, means for causing said main printing member to print upon said sections as they arrive in position, means for cutting the check strip, and means for actuating said cutting means each time said main printing member is operated.
19. In a machine of the class described, a main printing member having type wheels for printing amounts, two printing drums adapted to be rotated by the driving mechanism of the machine for printing upon different sections of a check strip, two check strip feed cams on one of said drums, each cam corresponding to one of said printing drums, adapted to feed the sections of the check strip into the field of operation of said main printing member, counter drums for said printing drums, means for controlling the counter

drum appurtenant to the drum having the feed cams thereon to selectively render effective said feed cams, and means for controlling the other counter drum in conjunction with said last-mentioned counter drum to selectively render effective said printing drums corresponding to the effective operation of said feed cams.

20. In a machine of the class described, two printing drums adapted to be rotated by the driving mechanism of the machine, consecutive num-

ber type wheels on each of said drums, means for advancing said type wheels, means for selectively feeding a check strip a varying amount to be printed upon by one or both of said printing drums, and means for simultaneously disabling said feeding device and said advancing means for said type wheels.

AUGUST RADERMACHER.
